STAND FOR SUPPORTING ROTARY MACHINE
TOOL CUTTERS WHILE BEING ATTACHED TO
MACHINE SPINDLE

William J. Rogers, 6121 W. Mitchell St.,
West Allis, Wis. 53214

Filed July 3, 1968, Ser. No. 12,627

Term of patent 7 years

Int. Cl. D15—05

U.S. Cl. D54—13

Fig. 2.

Fig. 3.

FIGURE 1 is a perspective view of a stand for supporting rotary machine tool cutters while being attached to machine spindle embodying my new design;

FIGURE 2 is a side view thereof;

FIGURE 3 is a top plan view thereof; and

FIGURE 4 is an end view thereof.

I claim:

The ornamental design for a stand for supporting rotary machine tool cutters while being attached to machine spindle, as shown.
